UNITED STATES PATENT OFFICE.

FRANK SIMA, OF WHITESTONE, NEW YORK.

RETAINING DEVICE FOR WINDOW PANES.

1,413,497.

Specification of Letters Patent. Patented Apr. 18, 1922.

Application filed May 11, 1921. Serial No. 468,624.

To all whom it may concern:

Be it known that I, FRANK SIMA, a citizen of the United States, and a resident of Whitestone, in the county of Queens and 5 State of New York, have invented a new and Improved Retaining Device for Window Panes, of which the following is a full, clear, and exact description.

This invention relates to retaining means 10 for window panes and seeks for one of its principal objects to provide a simple, inexpensive and effective means for positively retaining the glass in the frame against displacement.

15 The invention further contemplates a retaining means which is designed to co-operate with a small quantity of putty for sealing the juncture of the edges of the pane with the window frame, in which said means 20 operate to completely cover and house the putty to protect the same against the action of the elements.

A further object of the invention resides 25 in the provision of a combined retaining and housing strip which is preferably constructed from malleable metal which may be readily cut into the desired lengths to co-operate with windows of various sizes.

With the above recited and other objects 30 in view, the invention resides in the novel construction of the strip and the manner in which the same is employed, reference being had to the following specification, the appended claims and the accompanying drawings, in which—

Figure 1 is a fragmentary elevation of a window equipped with a retaining means constructed in accordance with the invention.

40 Fig. 2 is an enlarged fragmentary horizontal sectional view taken approximately on the line 2—2 of Fig. 1.

Fig. 3 is an end view of the retaining strip removed from the window.

45 Referring to the drawings by characters of reference, 10 designates the window frame provided with the usual rabbet 11 for the reception of the pane 12. The retaining device consists of an angular strip preferably 50 of malleable metal or any other suitable material which may be employed and which will perform and function in the desired manner. The strip comprises a base flange 13 which is provided with a line of spaced 55 perforations 14 for the reception of the nails, screws or other fastening elements 15 adapt-

ed to be passed therethrough and driven home into the frame. A right angularly disposed covering flange 16 is designed to project inwardly from the base flange 13 and lie 60 parallel to the surface of the window pane. The inner free extremity of the cover flange 16 is beveled as at 17 and the face of said covering flange which confronts the window pane is provided with a longitudinally extending V-shaped notch 18 adjacent the outer free edge.

In practice the pane 12 is positioned in the rabbet and may be secured in place by the usual glazier's points; the putty 19 is 70 then applied to fill the space between the edge of the glass and the wood and the retaining and covering strip is secured in place by attaching the base flange 13 in the rabbet of the window with the covering flange 16 75 arranged parallel thereto and in spaced relation with respect to the glass. Putty is then inserted in the space between the covering flange and the glass to completely fill the same. The beveled extremity 17 is then bent 80 inwardly to bring the confronting faces of the V-shaped notch into contact, thereby disposing the beveled extremity at an angle whereby its pointed end will contact with the pane. This will serve to completely 85 cover and house the putty and protect the same against the action of the elements and at the same time constitute an additional and auxiliary means which will positively retain the glass against displacement. The 90 strips may be manufactured in lengths which are cut and mitered at the opposite ends to snugly fit the window irrespective of its dimensions.

It will thus be seen that a simple and effective retaining means for window panes is 95 provided which operates in conjunction with the putty for holding and sealing the glass in place and which serves to protect the putty against deterioration.

100 While there has been illustrated and described a single and preferred embodiment of the invention, no limitation is necessarily made to the precise structural details, as it is to be understood that variations and modifications which properly fall within the scope 105 of the appended claims may be resorted to when found expedient.

Having thus described my invention, what I claim is:

110 1. An auxiliary retaining means for puttyed windows comprising an angle strip hav-

ing a base flange adapted to be secured to the window frame and a covering flange adapted to be arranged parallel to the puttied edges of the pane, said covering flange having a 5 V-shaped notch extending longitudinally of the inner confronting face adjacent its outer free edge, said notch defining together with the free edge an extremity adapted to be bent inwardly into engagement with the pane for 10 completely housing the putty and coacting with the glass to assist in retaining the same in place.

2. An auxiliary retaining and putty covering means for puttied windows comprising 15 a metallic strip having a base flange adapted to be secured to the window frame and a right angularly disposed covering flange adapted to extend over the putty, said covering flange having a V-shaped groove extending longitudinally of the confronting inner surface thereof adjacent its outer free edge to define together with the free edge thereof a bendable extremity engageable 20 with the pane when the confronting faces of the V-shaped groove contact whereby the putty is completely housed and auxiliary retention of the pane is obtained.

25 3. The combination with a window sash, a

pane of glass mounted therein and putty for sealing and retaining the said glass in place, 30 of an auxiliary retaining putty covering means consisting of a metallic strip of angular formation having one flange secured to the window sash, the other flange projecting parallel to the pane, said latter flange having a beveled outer extremity and a V-shaped groove on its inner face defining between said groove and the free edge of the latter flange an inwardly bendable extremity 35 for covering the exposed portion of the putty and for engagement with the pane.

4. As a new article of manufacture, a device of the character described, comprising a metallic strip of angular formation having an attaching flange and a covering flange, 45 said covering flange having its outer free edge beveled and its inner free edge provided with a longitudinally extending V-shaped notch, the attaching flange adapted to be secured to a window sash with the covering flange parallel to the window pane to cover the putty and the beveled edge bent 50 inwardly against the window pane to assist in retaining the same in place.

FRANK SIMA.
